LOUVERN G. LANGE, OF PASSAIC, NEW JERSEY.

RECEPTACLE CLOSURE.

Application filed October 21, 1927. Serial No. 227,635.

This invention relates to bottle sealing devices and more particularly to a bottle closure of simple design and construction that may be used in various types of bottles and 5 jars.

In the manufacture of bottle caps, the tin plate or metal cap is coated with an oil lacquer while in the flat state before drawing, shaping and threading the cap. During the 10 formation of the caps, the metal flakes and breaks the lacquer film which permits the contents of the container to get under these flakes, when the caps are put in use, and set up corrosion. When screw caps are employed as bottle closures they are usually sealed by placing a cardboard, feltboard or cork washer of resilient nature in the top of the cap and this washer is faced with tinfoil or varnished paper about .005" in thickness 15 to resist the contents of the container. The use of these washers is accompanied by several disadvantages, one of which is the added cost of the resilient board.

In packing goods that are sealed under 20 vacuum pressure, rubber gaskets are now employed which are very expensive. The product so packed frequently will react with the lacquer coating on the metal cap and set up corrosion and rust. This difficulty is encountered particularly with olives. Cardboard washers cannot be used in connection 25 with goods packed under vacuum pressure as most of the products sealed under vacuum are retorted under live steam or hot water and this wets the cardboard and destroys the resilience so that at the present time the use 30 of rubber gaskets is the only feasible method of sealing goods packed under vacuum pressure.

According to my invention I provide a 35 lining for a bottle cap or jar closure consisting of a relatively thick sheet of paper, having a thickness of about .006" to .008", and this paper is saturated with a flexible resilient varnish. This varnished paper lined 40 cap will stand retorting and take the vacuum pressure without leaking and will also resist reaction with any commodity which is now being packed. It may also be used in 45 place of the thick cardboard washers now employed with products that are not packed under vacuum pressure and will prevent the 50 contents of the container from coming in contact with the cap where the metal has flaked and broken the lacquer film and will 55 thus prevent corrosion from this cause.

In forming the lining either of two methods may be employed. In the first method a thick sheet of paper around .006" to .008" is saturated with a flexible varnish which 60 is resilient and is then coated on one side with one or two coats of a semi-resilient varnish that will resist the contents of the container. The uncoated side of the paper is then glued to the metal which has already 65 been given the customary coating on both sides with oil lacquer. The cap is then drawn or shaped, and threaded or beaded if necessary with the varnished paper on the inside of the cap completely covering the 70 entire inner surface of the cap so that the contents of the container will come in contact with the liner when the cap is in use and will not contact with any portion of the metal cap. 75

As an alternative procedure, the paper may be glued to the metal before it is coated and then saturated with the varnish and coated. The last coating of the paper may be applied simultaneously with the coating 80 of the metal thus eliminating the separate step of oil lacquering the tin plate. After the metal and paper lining have been prepared in this manner, the cap may then be drawn or shaped, threaded and beaded in the 85 usual manner. The lining after being saturated and coated with varnish has a thickness of from .010" to .012" and is capable of producing a hermetic seal with or without vacuum pressure. It may thus be used in 90 place of the usual cardboard or cork washer employed with crown caps and has the advantage over such washers that it contacts with and covers the entire inner surface of the cap effectually preventing the contents 95 of the container from contacting with the metal cap causing corrosion if the lacquer film on the cap is broken. In addition, it will stand the usual retorting processes for processing the contents of containers and 100 will not lose its resilience. It is, therefore, capable of use in closure members employed on commodities that are to be sealed under vacuum pressure in place of the rubber gaskets now employed and will prevent the 105 contents of the container from contacting with the metal of the cap and will thus eliminate corrosion.

In the accompanying drawings I have illustrated several forms of the invention. 110 In the drawings,

Fig. 1 is an elevation, partly in section,

of a jar or container provided with a beaded mouth showing a cap applied thereto with the lining of the present invention employed in the cap;

5 Fig. 2 is a sectional view of the cap shown in Fig. 1 prior to its application to the jar;

Fig. 3 is a sectional view of a jar or closure with a threaded mouth showing my invention applied to the cap; and,

10 Fig. 4 is a similar view of a bottle having a crown seal or cap with the invention applied.

Referring to Figs. 1 and 2 of the drawings, the reference numeral 1 designates a jar or container of conventional type having a bead 2 formed around its mouth. This jar or container is adapted to be closed by a cap 3 which is provided with a flange 20 or skirt 4 adapted to fit over the bead and to be curled or rolled around the bead as indicated at 5 in Fig. 1 of the drawings to retain the cap in position. In applying my improved lining to this cap, the lining is arranged on the inner side of the cap as indicated at 6 and extends downwardly to the bottom of the flange 4 as indicated at 7 so that the entire inner surface of the cap is covered by the varnished paper and the contents of the container are only able to contact with the varnished paper which will resist reaction and will prevent the contents from contacting with any portion of the metal cap. In Fig. 3 of the drawings, the container 8 is provided with external threads around its mouth and the cap consists of a disc 9 having a threaded flange 10. The varnished paper lining 11 is applied to the

cap before the cap is drawn and threaded and the lining extends over the inner surface of the flange as indicated at 12.

40 Similarly in a crown seal, the cap 13, shown in Fig. 4 is provided with a lining 14 of varnished paper and the lining extends downwardly as at 15, coextensive with the crimped flange 16 of the cap.

45 I claim:

1. A bottle closure comprising a metal cap and a fibrous lining arranged in said cap and covering the entire inner surface thereof, said lining being impregnated with varnish.

50 2. A bottle closure comprising a metal cap and a fibrous lining arranged in said cap, said lining being of sufficient thickness to form a seal and covering the entire inner surface of said cap, said lining being impregnated with varnish.

55 3. A bottle closure comprising a metal cap, and a lining for said cap, said lining consisting of paper from .006" to .008" thick, impregnated and coated with varnish to form a lining of from .010" to .012", said lining covering the entire inner surface of said cap.

60 4. A bottle closure comprising a metal cap having a coating of oil lacquer, and a paper lining of from .006" to .008" thickness glued to the inner side of said cap and covering the entire inner surface thereof, said lining being impregnated with varnish and coated with a layer of varnish on its exposed surface.

65 5. In testimony whereof I affix my signature.

LOUVERN G. LANGE.
